CLOTHESLINE SUPPORT AND HOLDER

Nicholas Zwald, Philadelphia, Pa.

Application December 14, 1938, Serial No. 245,718

2 Claims. (Cl. 211—119.17)

My invention relates to a combined line support and holder and more particularly to a combined clothesline support and holder.

One of the principal objects of my invention is to provide a combined clothesline support and holder equipped with means whereby the clothesline may be lowered to a selected position above the floor or ground to facilitate the attaching and removal of clothes thereto and secured in a raised position to effect drying of the clothes and prevent contact of the clothes with persons and other objects passing beneath said line during the drying of the clothes.

Another object of my invention is to provide a device of the above described character which is simple in construction, efficient in use, easy of attachment to supporting surfaces and economical in manufacture.

Other objects and advantages will be apparent from the following description, appended claims and annexed drawing.

Referring to the drawing wherein like reference characters designate like parts throughout the several views:

Figure 1 is a cross sectional view of the upper portion of a room or the like illustrating my invention attached to the opposed walls thereof.

Figure 2 is a front elevation of one of the pair of support and holder units comprising my invention.

Figure 3 is an enlarged detail sectional view taken on the line 3—3 of Figure 2.

Figure 4 is a detail perspective view of one of the brackets.

Figure 5 is a sectional view taken on the line 5—5 of Figure 3.

Figure 6 is a front elevation of a modified form of one of the support and holder units.

Figure 7 is an enlarged sectional view taken on the line 7—7 of Figure 6.

In practicing my invention, in a preferred embodiment illustrated in Figures 1 to 5 inclusive, I provide a pair of vertically extending elongated support brackets 5 having offset end sections 6 secured to the opposite sides 7 of a room by means of suitable screws or the like. Each of the brackets is fashioned along one side with inwardly extending arcuate shaped slots 8 having inner end sections terminating below the inner walls 9 to form seats 10 for a purpose herein-after set forth. Slidably mounted on each of the brackets are elongated yokes 11 having marginal edges 12 overlying the inner faces 13 of the brackets whereby to maintain said yokes in slid-able and connected relation with the brackets.

Each of said yokes are fashioned with an arcuate shaped slot 14 adapted for selective registry with one of the slots 8 formed in the respective bracket. Pivotally mounted on the outer face of each of the yokes is one end of a latch arm 15, the opposite end of said arm being equipped with a latch pin 16 operable through the slot 14 and through a registering slot 8 of the respective bracket. The pin 16 is adapted to be positioned within the seat 10 to prevent accidental dislodgement of the pin therefrom and resultant undesired downward movement of the yoke.

The outer end of the pin 16 is fashioned with a collar 17 for engaging the inner face 13 of the bracket whereby to lend rigidity to the structure when in adjusted position and also to prevent outward movement of the pin through the seat 10.

The outer faces of the upper ends of each of the yokes are equipped with fastening devices or hooks 18 for attachment of the ends of a clothesline 19 extending between the respective units.

From the foregoing it will be apparent that when the arm 15 is moved out of the slots 14 and 8 the yokes may be lowered to facilitate access to the clothesline 19 and raised to dispose the clothesline a desired distance above the floor or ground and maintained in adjusted position by the engagement of the pin 16 within selected slots 8.

30 In the modified form illustrated in Figures 6 and 7 the yoke 20 is provided with folded ends 21 slidably engaging the outer face 22 of the bracket and said bracket is fashioned with the arcuate slot 23 located intermediate of the width

35 thereof and accommodates the locking pin 24. The body or connecting section of the yoke is fashioned with a vertically extending slot 25 fashioned with laterally extending arcuate shaped slots 26 formed with seats and register-
ing with the slot 23. The pin 24, as in the in-

stance of the preferred embodiment, is mounted on one end of an arm 27, the opposite end being pivoted to the outer face of the bracket as at 28. When the arm is disposed to one side of the slot 23, the pin 24 is adapted to operate in the slot 25 to permit vertical adjustment of the yoke 20.

When the slot 23 is in registry with one of the slots 26 the arm is operable to seat the pin 24 within the closed ends of the registering slots 50 thereby securing the yoke in adjusted position on the bracket 22.

In both the preferred and modified forms the arms 15 and 27 respectively are provided on the ends adjacent the locking pins 16 and 24 with

finger pieces 30 to facilitate movement of the arms.

What I claim is:

1. A device of the character described comprising a bracket member adapted to be fixed to a support, the said bracket member having spaced arcuate slots extending transversely from an edge thereof, a yoke member disposed in face to face relation with the bracket, the said yoke having side portions bent over to slidably engage the side margins of the bracket and a slot therein corresponding to the slots of the bracket and adapted to assume longitudinal registry with said bracket slots, a line fastening element carried by the yoke member, and an arm pivotally mounted on the said yoke having a locking pin thereon movable into registration with the slots in the bracket and yoke for locking the yoke in selectively adjusted position on the bracket.

2. A device of the character described com-

prising an elongated flat bracket member adapted to be fixed to a support, the said bracket member having longitudinally spaced arcuate slots extending transversely from and opening at an edge thereof, a yoke member having a flat body disposed in face to face relation with the bracket, the said yoke having opposed side portions bent to form channels slidably engaging the side margins of the bracket and having an open slot therein identical to the slots in the bracket adapted to assume longitudinal registry with the bracket slots, a line fastening element carried by the yoke member, and an arm pivotally connected to the yoke at one end and carrying a locking pin at the free end, the said pin being movable into the registering bracket and yoke slots through the open ends thereof to lock the yoke in selectively adjusted position on the bracket.

NICHOLAS ZWALD.
